UNITED STATES PATENT OFFICE.

JOHN HENRY SPALDING, OF REGINA, SASKATCHEWAN, CANADA.

PATTERN DRAFTING.

Application filed March 23, 1926. Serial No. 96,725.

This invention relates to a new drafting system for the production of coats and other like garments, and my improvements are characterized as embodying the following 5 features:

(1) The system provides a natural foundation or basic line, which I call the construction line, and with which all the important measurements are applied, this construction line extending across the breast, at 10 the base of the scye.

(2) The system enables all the controlling points of contact to be fixed without error.

(3) The system replaces the usual strap 15 measure by a height line which brings together in the gorge contact lines that are necessarily separated in other systems of cutting, thereby automatically preventing those errors from arising which heretofore have 20 caused the problem of the straight and crooked shoulder.

(4) The system makes short measurements easy of application.

(5) The system provides for over-erect 25 and stooping figures when applied on its sweep, having regard for variations in height.

(6) The system provides mathematically 30 for variations in height of the person to be fitted, while retaining accurate body conformation, and when applied on its sweep automatically provides for stooped and over-erect figures.

(7) The system includes in the drafting 35 correct allowances for make-up (excepting the seat measurement.)

(8) In addition to the foregoing advantages the system comprises a double-draft and is thereby rendered self-balancing and 40 self proving.

Other features and advantages of my invention will hereinafter appear.

The drawing is a representation in plan 45 of the lines comprising the draft comprehending my improved system.

With the drafting systems at present in vogue it is difficult if not impossible to accurately apply the short measurements taken from the live figure, mainly because in said 50 systems the gorge is divided from the nape, leaving the cutter without a basic point from which to work. Whereas under my new drafting system I include in the draft the complete gorge. This enables me to establish 55 a height line, in place of the usual strap

measure, that extends from the centre of the construction line to the nape.

It is by means of this height line, so located, that I am able to vary the height of the draft, without interfering with other 60 measurements.

Then in addition to the height line I provide for a sweep which extends in an arc drawn from the front centre on the construction line to the height line, being produced from a pivotal centre at the intersection of the centre back line and construction line. This sweep is modified by the extent of the height line according to the 65 height measure desired.

The characteristic features of the draft which in part have thus far been referred to, are in my improved system duplicated in an angularly disposed adjunct to the original draft, as will be made to appear in the following description, the purpose of the duplication, or double draft being that one draft 70 may be checked or verified by the other.

Now referring to the drawing, it will be noted that I have established three lines in 75 the form of an approximately equal sided triangle, having the base line that extends horizontally from O to *1 and the upwardly converging lines that extend respectively from O to ** and from *1 to ** designated 80 breast line 1 and breast line 2 respectively.

Construction line O-*1 is the breast 85 measure. The extension *1 to *2 represents 2 $\frac{1}{4}$ " added for make up. *3 on line O-*2 is the midpoint between O-*2. Line O-*4 90 is a vertical duplication of line O-*2, and serves to enable me to locate point A on the sweep which emanates from *2, using O as the pivot, the point A forming the nape of the neck.

Point A is located by using a right angle square and by having the edge of one blade lying upon the point *4 and the edge of the other blade lying upon the point *3.

Having now established the nape of the neck at A, straight lines are drawn from A 95 respectively to *3 and *4, these lines each being both front height lines and back centre lines in the double system. Care is necessary in adjusting the square accurately as otherwise the balance of the draft would be astray.

Parallel with the front height line extended from A-*3 is a check line that 100 extends from B to C on the construction line 105

O—*1 one inch from said front height line. Also extended between the construction line and the point B is a line that is right angular to said construction line, joining it at D, and serving to define the base of the gorge. The point E on line B—D is distanced $\frac{1}{6}$ th breast measure from A, or it may be otherwise suitably distanced, since this point E marks the front shoulder point of the gorge. The reason that E is the shoulder point is because it fixes the width of the top of back desired; F then becomes the gorge and lapel line.

The point E on line D—B is distanced 15 $1\frac{1}{4}$ " more or less, from point F, to gauge the form of the lapel.

Between A and G on the sweep line A—*2 is $\frac{1}{3}$ rd of breast measure. To define the lapel the square is placed with its angle on F, arm on G and then I draw forward lapel line 1 and draw downward the dotted line to H on construction line O—*1.

With the square resting on check line B—C the short line E—I can be drawn, this line E—I serving as a check, as will herein-after appear.

Now the gorge is shaped from point A through E and G as shown.

The distance represented between the points A and OO is one half the breast measure. In the example illustrated, assuming the breast measure to be 38" and the corresponding height of the model being 5' 5", then it happens that the number of unit inches in the breast measure equal the number of inches additional to the number of feet in the height measure, and this relation holds good with other breast and height measures.

40 The line connecting A and *4 I will now designate centre line 2. If the square be now placed on centre line 2, with its short arm pointing toward A and its long arm resting on O, a construction line or breast line 1 can be drawn between O and OO. A to OO defines depth of scye, and O to AA also defines depth of scye; and when O and OO are connected, the breast line 1 is thereby formed.

50 Breast line 1 can be extended a short distance.

Remembering that the line AA from O is a duplication of the line A—OO, a top height line is drawn forward at right angles 55 from AA and connects with the front height line that extends between A and *3.

The line BB, parallel with the line AA that connects with line BC is a check line extending to CC, and corresponds to the 60 check line BC.

In order to locate breast line 2, measure and connect *1 and ** by applying the breast measure, plus $2\frac{1}{4}$ ".

With the long arm of square resting on 65 breast line 2 and *1, the short arm on BB,

I mark forward to DD, the line BB, DD thus formed being a duplicate of line BD. Now it will be found that the line AA—EE duplicates the line AE. The distance between FF and EE on the line BB—DD corresponds with the distance between EF on line BD.

Perpendicular to line O—*2 I draw the short line II, EE, this short line corresponding with the line EI. It will be noted that these short lines II, EE, and EI, although corresponding in their respective placements and functions, have been produced by different means.

The portion of breast line 2 between DD, HH corresponds with the portion of the construction line between D and H.

The duplicate lapel line can now be drawn by placing the angle of the square on FF and resting its arm on HH, indicated by a dotted line, and then squaring forward the lapel line 2, shaping gorge 2 from AA through EE and GG, to correspond with gorge 1.

With tape held in the left hand, using *1 as a pivot, the tape is swept forward from AA to **, thereby forming the back incline sweep, which corresponds to the front incline sweep. The sweep portion AA, GG is a duplicate of the sweep portion AG.

To locate the front of scye I divide the breast measure, which, in the present example is 19 inches, into two equal measures of $9\frac{1}{2}$ inches, then I deduct 2 inches from the front of scye and add 2 inches to the blade. The front of scye measure is now $7\frac{1}{2}$ inches, and the blade measure is $11\frac{1}{2}$ inches. One quarter inch is now added to front of scye, from J to K; otherwise, in the make up the scye would lose one seam or quarter inch, and the blade would gain the same. The usual allowance for make up has already been provided for in the drafting.

The distance between J and L is one fourth of breast measure, with $\frac{1}{2}$ inch added. To define the width of arm scye I now square up from the construction line at both K and L.

The point M from K is one sixth of breast measure. To locate the back shoulder point N, I connect M and EE, intersecting line L'. Now, for the front shoulder seam I connect N with E, then measure front shoulder seam from E to N to correspond with back shoulder seam from EE to N; shape shoulders and front of scye.

The point o on construction line is $\frac{3}{4}$ " from O. With square resting on M and o: note where it crosses line L', finding P, to locate the top of side seam.

In producing the body part of the coat, from AA, I mark down on centre line 1, then measure 17" for waist, $24\frac{1}{2}$ " for seat,

and $30\frac{1}{2}''$ for length, then square these measures forward.

Then from AA I draw a line through o, extending that line to Q at waist line, then 5 square down from Q, through R to S at bottom of back. From AA I shape back seam as shown on draft through o to Q.

The distance from the point T from L on construction line is $\frac{1}{2}''$. Square down 10 to waist line.

To have uniform width of back I measure from T to o and apply the same measure from S to U at bottom of back, and then connect from U to T at waist. Then I 15 shape back of scye from N to P, and allow $\frac{1}{4}''$, for seam, as shown, forward of P; thence shaping side seam of back through V to U to bottom.

With short arm of square resting on construction line, at a point $\frac{3}{4}''$ forward of *1, I square down from seat line W to bottom of front. Also square down from *2 to bottom of coat.

With the seat measure $19\frac{1}{2}''$, or $\frac{3}{4}''$ more 25 than breast measure, the figure and attitude both being normal, I measure on the seat line from centre line 1 to R and add $\frac{3}{4}''$ thereto—that being the difference between the breast and seat measures, and apply 30 that amount from V to X on the seat line.

The waist measure, here represented as 17", or 2" less than breast measure, allowing for seams, is now shaped from the back side seam at P, through X and Y, giving 35 the effect desired.

Using P as a pivot, I sweep from U at bottom of back to Y at bottom of fore part. With the tape on A, nape of neck, I carry it across draft to S at bottom of back, then 40 apply that measurement from AA to W at bottom of fore part, and connect Y and W, to shape the bottom of draft.

For the button stand I add 2", more or less from *2 forward, then square to bottom 45 and shape front.

To crease the lapel I advance from point E $1\frac{1}{4}''$ and draw a line connecting with top button.

In delineating the pocket I square down 50 from K $\frac{2}{3}$ rd of sleeve length, measure up from bottom and divide the pocket width half and half of scye line.

To produce the under arm cut I measure 55 $\frac{3}{4}''$ forward on construction line from *3 to Z, measure from Z to o, apply from waist

line at Q, forward, and connect with Z, then shaping the arm seam as shown. The under arm seam will then follow any attitude the draft may assume.

On breast line 2 I add 2" from **, square 60 forward, and shape lapel to correspond with the front draft.

The top balance sweep, shown by a dotted line, is found by using *3 as a pivot and forming an arc from A to AA, this sweep 65 connecting the two napes, and proving the accuracy of the draft by the double system.

Variations within the spirit and scope of my invention are equally comprehended by the foregoing disclosure. 70

I claim:

The method of obtaining a pattern for a coat consisting in taking the circumferential body measurement of the wearer across the breast and under the arm pit, laying off 75 one-half of said measurement in a straight line upon a sheet forming a construction base line, using the construction line as a base and erecting thereon an isosceles construction triangle the sides of which are 80 equal in length to the length of the construction base line and with the apex of one of the base angles thereof coincident with one end of the construction line, the apex of the other base angle of the construction 85 triangle lying upon the construction base line at a point between the ends thereof, erecting a perpendicular line from the end of the construction base line which is coincident with the apex of the base angle of 90 the construction triangle, said perpendicular line being equal in vertical height to the horizontal length of the construction base line, locating a point upon the base construction line midway between the ends 95 thereof, laying off a right angle with the said midway point upon the base construction line and the upper end of the perpendicular line at the end thereof as the ends of the side lines of the said right angle, 100 using the midway point upon the base construction line as a center and with a radius equal to the distance between said point and the apex of said angle, striking an arc which intersects the perpendicular line at the edge 105 of the nape and then laying off corresponding nape and gorge lines at the opposite ends of said arc.

Executed this 16th day of March, 1926.

JOHN H. SPALDING.
